United States Patent Office

Des. 183,760

Patented Oct. 21, 1958

183,760

BOTTLE

Roscoe Meadows, Warwick, Va., assignor to Roscoe Meadows, Jr., Warwick, Va.

Application June 13, 1958, Serial No. 51,350

Term of patent 14 years

(Cl. D58—6)

FIG.1

FIG.2

Fig. 1 is a perspective view of a bottle showing my new design; and

Fig. 2 is a top plan view thereof.

The side of the bottle not shown is the same as the side shown. The end not shown is plain.

The dominant features of my design reside in the portions shown in full lines on the drawing.

I claim:

The ornamental design for a bottle, as shown and described.
